UNITED STATES PATENT OFFICE.

PETER HAYDEN, OF COLUMBUS, OHIO.

DESIGN FOR A CHAIN-LINK.

SPECIFICATION forming part of Design No. 25,631, dated June 16, 1896.

Application filed May 6, 1896. Serial No. 590,495. Term of patent 14 years.

To all whom it may concern:

Be it known that I, PETER HAYDEN, a citizen of the United States, residing at Columbus, in the county of Franklin and State of Ohio, have invented or produced a new and original Design for Chain-Links, of which the following is a specification.

This design has for its object to provide a novel chain-link, which possesses a peculiar configuration, and presents an ornamental or distinguishing appearance to the eye.

The leading feature of the design resides in a chain-link having an approximately semicircular end member, converging side members and substantially parallel, rectilinear shanks extending from the converging side members and provided with circularly-bent or ring-shaped ends which lie beside each other.

The invention is illustrated by the accompanying drawing, in which the figure is a perspective view of a chain-link made according to my design.

In the accompanying drawing, the numeral

1 indicates the semicircular member; 2 and 25 3, the converging side members; 4 and 5, the substantially parallel, rectilinear shanks, and 6 and 7 the circularly-bent or ring-shaped ends. The substantially parallel rectilinear shanks lie contiguous, and the ends of these 30 shanks are bent in reverse directions to form the circularly-bent or ring-shaped ends 6 and 7, which ends lie beside each other.

The design provides a novel chain-link, which is ornamental, possesses a peculiar 35 shape, and presents a characteristic and distinguishing appearance to the eye.

What I claim is—

The design for a chain-link, substantially as shown and described.

In testimony whereof I have hereunto set my hand in presence of two subscribing witnesses.

PETER HAYDEN.
